G. W. HEATH

PENCIL

Filed July 29, 1922

Inventor

George W. Heath

By his Attorney

Manuel Block

UNITED STATES PATENT OFFICE.

GEORGE W. HEATH, OF EAST ORANGE, NEW JERSEY, ASSIGNOR OF ONE-HALF TO
ALFRED C. HEATH, OF EAST ORANGE, NEW JERSEY.

PENCIL.

Application filed July 29, 1922. Serial No. 578,291.

To all whom it may concern:

Be it known that I, GEORGE W. HEATH, a citizen of the United States of America, residing at East Orange, Essex County, State 5 of New Jersey, have invented certain new and useful Improvements in Pencils, of which the following is a specification.

This invention relates to improvements in magazine pencils, one of the objects being to 10 provide means whereby the nozzle end of the pencil, or end which projects beyond the end of the casing, when the pencil is in use, can be rigidly supported beyond the end of the casing, said rigid support being provided 15 by means operable by the movement of the nozzle as it is projected forwardly. When the nozzle is retracted, the supporting means will be operated to remove pressure from the nozzle so that said nozzle can be easily 20 moved.

A further object of my invention is to provide an improved magazine for extra leads and a closure therefor which is not normally removable from the pencil as a whole, but 25 which is slidable longitudinally of the element which operates the device for projecting and retracting the lead carrier, said closure acting to prevent the spare leads from dropping out of the magazine, en masse, 30 when the closure is disconnected from the casing. The foregoing is a mere outline of my invention, a more detailed description of which will follow.

I will now proceed to describe my invention in detail, the novel features of which I will point out in the appended claims, reference being had to the accompanying drawing, wherein:

Fig. 1 illustrates a fragmentary sectional view of a magazine pencil, having my improved clamp to impart rigidity to the nozzle of the pencil;

Fig. 2 is a similar view of the nozzle of the pencil illustrating the clamp in clamping 45 position;

Fig. 3 is a sectional detail view partly in elevation, illustrating a portion of the lead carrier, the sleeve carrying same, and my improved clamp;

Fig. 4 is a longitudinal sectional view, partly in elevation, illustrating the complete pencil, the nozzle end being broken off;

Fig. 5 is a side elevation illustrating the lead carrier operating sleeve extended for

the purpose of removing spare leads from 55 the magazine;

Fig. 6 is an end view, looking from the left in Fig. 4, of the casing of the barrel illustrating the outer sleeve which supports the lead operating mechanism, and the end 60 head carried thereby;

Fig. 7 is an enlarged cross sectional view on line 7—7, Fig. 4, illustrating a few leads in the magazine;

Figure 8 is an enlarged view of the lead 65 carrier and its operating parts, some of which are broken away to disclose other parts.

One of the objects of my invention is to provide means to impart rigidity to the lead-carrier of a magazine pencil when it is extended, in order that there will not be any looseness on the part of the lead-carrier while writing with the pencil. To accomplish this result, I provide a device which is 70 arranged to clamp the lead-carrier, when it is extended, the clamping action being effected automatically during the movement of the lead-carrier from the retracted to the extended position, but the lead carrier will 75 not be clamped until fully extended. To illustrate my invention, I have selected a magazine pencil comprised of a carrier 8 for the lead 9. The carrier 8 is provided with a pin 10 operating in a slot 11 extending longitudinally of a sleeve 12. The pin and slot 80 act to keep the lead-carrier from rotating. The pin 10 extends through said slot and engages a helical slot 13 in a sleeve 14 carried by sleeve 12. The sleeve 14 carries a rigid 85 pin 14^a, see Fig. 8, to engage a helical slot 15 in a sleeve 16 carried by sleeve 14. Over the sleeve 16 a sleeve 17 is fitted and secured thereto, usually by solder. Over the sleeve 17 is fitted an outer sleeve 90 95 18 which at its inner end 19 is soldered, as at 20, to a collar 21 fixedly carried by sleeve 12. Adjacent the end 19, outer sleeve 18 carries fixed thereto a flange 22 which fits the bore of a casing 23. A pencil 100 made up of the foregoing elements is well known. Hence, a more detailed description will not be given. When sleeve 17 is moved outwardly or extended, as indicated in Fig. 5, the lead-carrier will be extended as indicated in Fig. 2. When said sleeve 17 is pushed in, the lead-carrier will be retracted 105 as indicated in Fig. 4. The movement of

2
sleeve 17 operates the sleeve 16, having the helical slot 15, longitudinally of the pencil, which action rotates sleeve 14 having helical slot 13 for the reason that the pin carried by sleeve 14 engages the slot 15 and in traveling therethrough is revolved, thus revolving sleeve 14. When sleeve 14 is rotated, the lead carrier 8 will be moved longitudinally of the pencil due to the fact that the pin 10 attached thereto, will be carried along slot 11 by the movement given it in the slot of the sleeve 14. One of the objects of my invention is to firmly hold the carrier 8 when it is in extended position, as indicated in Fig. 2, to avoid lost motion between the lead carrier and casing while writing. One way in which I accomplish this result is to provide a collet or sleeve 24 which I mount loosely upon carrier 8, that is to say, slideable longitudinally of the carrier. In this instance the collet or sleeve 24 is split as at 25 to provide yieldable fingers 26 arranged to clamp or engage the carrier 8. To cooperate with the clamp, I provide the sleeve 12 with a tubular head 27 having a conical end 28 through which the lead carrier 8 passes. The clamp 24 operates within the head 27. The conical end of the head 27 fits the conical end 29 of the casing 23. It will be seen that the carrier 8 is reduced in diameter to provide (in this instance) a shoulder 30; the extent of the reduced portion 31 of the carrier will be approximately equal to the extent of longitudinal movement of said carrier.

When the lead carrier 8 is projected forwardly, by pulling sleeve 17 outwardly, the collet or clamp 26 will move toward the conical end 28 of the tubular head 27. It may here be stated that the collet or clamp will snugly fit the reduced portion of the lead carrier; hence, will move with it. When the collet or clamp 24 reaches the conical end of the head 27, it will slip upon the carrier until shoulder 30 is forced against same, which action will take place just prior to the completion of the outward stroke of the carrier. During the completion of the outward stroke of the carrier, the clamp 24 will be forced into the conical end of the head 27, as indicated in Fig. 2, thereby forcing fingers 26 firmly into contact with the carrier, after which the carrier will be rigidly supported, as there will not be any lost motion between it and the casing 23. When the lead carrier is retracted, the clamp 24 will be drawn out of the conical end of the head 27.

A further object of my invention is to provide an improved form of magazine for spare leads. To this end I provide the outer sleeve 18, which carries the flange 22, at one end with a head member 31 carrying lugs 32, in this instance four, each lug being connected to the flange 22 by a rod 33, said

rods dividing the space 34, between casing 23 and sleeve 18, into four compartments 35. The open end of the casing 23 is closed by a cap 36 having threads 37 to engage the interrupted threads 38 on the head member 31. The threads 38 are interrupted or cut away at 39 in alinement with the compartments 35 in order that the spare leads 40 can move freely out of the compartments. The cap 36 is counterbored slightly at 41 to provide a flange 42 for the outer end of the leads to rest upon when the pencil is inclined, as indicated in Fig. 5. It will be obvious that the leads will be engaged at both ends, one end being located in the annular groove formed by the counterbore 41, the other end being supported by the head member 31. By this means less breakage of leads will occur, also loss by dropping out of the magazine. The rods 33 prevent the leads from becoming jammed in the magazine by being turned too much at an angle relative to the axis of the pencil; in other words, said rods maintain the leads in a plane substantially parallel with the axis of the pencil. The cap 36 is slideable longitudinally of the sleeve 17 and is held against removal therefrom by a plug 43 fitted in the outer end of sleeve 17, the diameter of the plug being slightly more than the sleeve 17; hence, a stop will be provided to prevent the cap 36 from moving off the sleeve 17. The rods 33 at one end engage the collar 22 and at the other end they engage the lugs 32 on head 31. While the cap 36 is being unscrewed, the rods 33 will prevent the leads from being forced circumferentially around the sleeve 18 and broken. It will be apparent that the cap 36 is movable longitudinally along with the sleeve 17 while it engages the end plug 43 and draws the sleeve outward therewith for operating the lead carrier and it is arranged to uncover the open end of the magazine independently of the sleeve 17, but the cap 36 cannot be removed from the said sleeve 17. In short, the sleeve 17 can be operated to actuate the lead carrier without removing the cap from the casing, as said sleeve is slideable in said cap.

Referring again to the action of the collet or clamp 24, it is apparent that said collet will be forced between the carrier 8 and abutment or inclined surface 28 when said carrier is extended to its full extent; hence, said carrier will be held against sidewise movement.

What I desire to secure by Letters Patent is:—

1. In a pencil, a casing member, a movable lead carrier, means to project the carrier beyond one end of the casing and to retract same into the casing, a reduced portion on said lead carrier, and means slideably mounted on said reduced portion for

holding the lead carrier, rigid when in projected position.

2. In a pencil, a casing member, a movable lead carrier, means to project the lead carrier beyond one end of the casing and to retract same into the casing, a collet slidably mounted on said lead carrier, and means on said lead carrier for advancing said collet, and means for causing said collet

10 to grip said lead carrier.

3. In a pencil, a casing member, a movable lead carrier, means to project the lead carrier beyond one end of the casing and to retract same into the casing, a gripping member slidably mounted on said lead carrier, and means associated with said casing for causing said member to grip the lead carrier.

4. In a pencil, a casing member, a movable lead carrier, means to project to lead carrier beyond one end of the casing and to retract same into the casing, a collet member mounted upon said lead carrier, a head member having a conical end and surrounding one end of said lead carrier, and means whereby when said collet member engagess said head member it is caused to grip the lead carrier.

5. In a pencil, a casing member, a movable lead carrier, means to project the carrier beyond one end of the casing and to retract same into the casing, a split collet slidably mounted upon the carrier but arranged to move with the carrier, and an abutment having an inclined surface to close the collet upon the carrier when said carrier has been projected to its full extent, for the purpose set forth.

6. In a pencil, a casing member, a movable lead carrier, means to project the carrier beyond one end of the casing and to retract same into the casing, a split collet slidably mounted upon the carrier but arranged to move with the carrier, an abutment having an inclined surface to close the collet upon the carrier when said carrier has been projected to its full extent, for the purpose set forth, and means on the carrier to force the collet into contact with said inclined surface when the carrier has been projected to its full extent.

7. In a pencil, a lead carrier, a sleeve mounted thereupon having a longitudinal slot, a pin carried by the carrier movable along said slot, a lead screw engaging said pin, means to actuate the lead screw to project or retract the lead carrier, a tubular head carried by the sleeve surrounding the lead screw at one end thereof and surrounding the lead carrier, a clamping element carried by the lead carrier located within said head, and means carried by the tubular head to force the clamp into contact with the lead carrier when said lead carrier is fully projected for the purpose set forth.

8. In a pencil, a lead carrier, a sleeve mounted thereupon having a longitudinal slot, a pin carried by the carrier movable along said slot, a lead screw engaging said pin, means to actuate the lead screw to project or retract the lead carrier, a tubular head carried by the sleeve surrounding the lead screw at one end thereof and surrounding the lead carrier, a split collet slidably mounted on the lead carrier, said collet being located within said head, and means carried by the lead carrier to force the collet into contact with said tubular head, when the lead-carrier is fully protected for the purpose set forth.

9. In a pencil, a casing, a lead carrier within same, means to project the lead carrier through one end of the casing, said lead carrier passing loosely through the end of the casing, and means operable by the movement of the lead carrier to rigidly connect the casing and lead carrier when the latter is fully extended, said means comprising a collet, one end of which is adapted to be wedged between said casing and said carrier.

10. In a magazine pencil, a casing, a lead carrier within same, means to operate the carrier to project same beyond one end of said casing and to retract same, said carrier operating means passing through the opposite open end of the casing, a cap for the open end of the casing, slidably longitudinally along the operating means for the lead-carrier, and means to prevent the removal of the cap from said carrier operating means.

11. In a magazine pencil, a casing, a lead carrier within same, means to operate the carrier to project same beyond one end of said casing and to retract same, said carrier operating means passing through the opposite open end of the casing, a sleeve open at one end enclosing the lead carrier and its operating means, said sleeve being spaced from the casing to provide space for the storage of spare leads, a cap for the open end of the casing slidably longitudinally of the operating means for the lead carrier, said cap, at the end which contacts with the casing, being provided with an annular groove to support spare leads at the end which projects from the magazine when the cap is removed.

12. In a magazine pencil, a casing, a lead carrier within same, means to operate the carrier to project same beyond one end of said casing and to retract same, said carrier operating means passing through the opposite open end of the casing, a sleeve open at one end enclosing the lead carrier and its operating means, said sleeve being spaced from the casing to provide space for the storage of spare leads, a flange carried by said sleeve intermediate the ends thereof, a

head at the open end of the sleeve having a plurality of lugs, a rod connecting each lug on the head and the flange on the sleeve to provide a plurality of compartments for spare leads, and a cap for the open end of the casing, said cap being slidable longitudinally of the operating means for the lead carrier.

13. In a magazine pencil, a casing, a lead carrier within same, means to operate the carrier to project same beyond one end of said casing and to retract same, said carrier operating means passing through the opposite open end of the casing, a sleeve open at one end and enclosing the lead carrier and its operating means, said sleeve being spaced from the casing to provide space for the storage of spare leads, a flange carried by said sleeve intermediate the ends thereof, a head at the open end of the sleeve having a plurality of lugs, a rod connecting each lug on the head and the flange on the sleeve to provide a plurality of compartments for spare leads, and a cap for the open end of the casing, said cap being slidable longitudinally of the operating means for the lead carrier, said cap being provided with an annular groove at the end which contacts with the open end of the casing to support spare leads at one end, when said leads project from the magazine.

14. In a magazine pencil, a casing, a lead carrier within same, means to operate the carrier to project same beyond one end of said casing and to retract same, said carrier operating means passing through the opposite open end of the casing, a sleeve open at one end enclosing the lead carrier and its operating means, said sleeve being spaced from the casing to provide space for the storage of spare leads, a cap for the open end of the casing slidable longitudinally of the operating means for the lead carrier, and means associated with the cap to support spare leads, at one end when said leads project from the magazine.

15. In a magazine pencil, a casing, a lead carrier within same, means to operate the carrier to project same beyond one end of said casing and to retract same, said carrier operating means passing through the opposite open end of the casing, a sleeve open at one end enclosing the lead carrier and its operating means, said sleeve being spaced

from the casing to provide space for the storage of spare leads, a cap for the open end of the casing detachably connected thereto, and means to support spare leads at the end which projects from the magazine when the cap is removed.

16. In a magazine pencil, a casing open at one end, a lead carrier within same movable longitudinally thereof, means to operate the lead carrier, a sleeve encasing the lead carrier and its operating means, said sleeve being spaced from the casing to provide space for leads, means within said space to subdivide same into a plurality of compartments, each of which is arranged to hold a plurality of leads, a cap for the open end of the casing having a threaded engagement therewith, said cap being arranged to support spare leads at the end which projects from the magazine when the cap is removed, said cap being mounted for sliding movement on the body of said pencil.

17. In a magazine pencil, a casing, a lead carrier within same, means to operate the carrier to project same beyond one end of said casing and to retract same, said carrier operating means passing through the opposite open end of the casing and a cap for the open end of the casing, slidable longitudinally of the operating means for the lead-carrier.

18. In a pencil, a tubular support member, a non-rotatable lead carrier within same, slidable means also within the tubular support arranged to slide the carrier longitudinally of the support, and a casing for the tubular supporting member and lead carrier, said casing being spaced from the supporting member to provide a magazine for spare leads, and a cap for said magazine adapted to slide along the body of said pencil.

19. In a pencil, a tubular support member, a non-rotatable lead carrier within same, slidable means also within the tubular support arranged to slide the carrier longitudinally of the support, and a casing for the tubular supporting member and lead carrier, said casing being spaced from the supporting member to provide a magazine for spaced leads, and a cap for said magazine, said cap having a central opening therein through which the pencil body passes.

GEORGE W. HEATH.
